UNITED STATES PATENT OFFICE.

HARVE R. STUART, OF WHEELING, WEST VIRGINIA.

TELEPHONE.

No. 898,283.

Specification of Letters Patent.

Patented Sept. 8, 1908.

Application filed September 24, 1907. Serial No. 394,292.

To all whom it may concern:

Be it known that I, HARVE R. STUART, a citizen of the United States, residing at Wheeling, in the county of Ohio and State 5 of West Virginia, have invented certain new and useful Improvements in Telephones, of which the following is a full, clear, and exact description.

My invention relates to an instrument for 10 magnetically recording and reproducing sound and known as the telephone.

The invention is more particularly applicable to what is known as a disk machine in which a flat steel disk is continuously rotated 15 in close proximity or contact with a recording and reproducing magnet mounted on a carriage which moves radially with respect to the disk, and traces a spiral magnetic path or record thereon.

20 The present invention pertains specially to the construction of said carriage, and while described particularly in use with a disk machine is not limited thereto, being equally applicable to all the other types of 25 machine in which a movable carriage is used.

In machines of the above character it is always necessary for the recording and reproducing magnet to be maintained in very close proximity or actual contact with the 30 recording medium at all times. But since the recording medium must be frequently removed and replaced, it is evident that it is ordinarily practically impossible to have such medium revolve or move in a perfectly 35 true unvarying path of revolution or movement. For example, in the disk machine where the disks are repeatedly being removed and changed, it is wholly impractical to have the mechanism so accurate and the adjustment 40 so perfect that there will never be any slight lateral or wabbling movement.

In accordance with the present invention the disk or recording medium is mounted so as to be quickly and expeditiously removable, and no special attempt is made to secure absolute accuracy in the movement of revolution. Special means are, however, provided by which any slight movement of the disk out of its proper plane of rotation is 50 compensated for by a corresponding movement of the magnet or magnets of the carriage, so that the latter keep in permanent and unvarying contact with the disk at all times. For this purpose I employ a carriage 55 having means for maintaining the operating magnet or magnets pressed lightly against

the recording medium, and I so arrange this mechanism that it is wholly independent of the carriage feed and carriage returning functions.

60 The invention also includes certain additional features of the carriage mechanism by which the feed and return thereof are made in a very convenient, simple and efficient manner.

65 In the drawing: Figure 1 is a top or plan view of a telephone embodying the principles of my invention; Fig. 2 is a vertical sectional view of the same; Fig. 3 is a detail top plan view showing the carriage mechanism; Fig. 4 is a section of part of the carriage mechanism; this section is taken on the line IV—IV of Fig. 5; Fig. 5 is a section on the 70 line V—V of Fig. 4; and Fig. 6 is a perspective view of part of the same.

75 Referring to the drawings in which like parts are designated by the same reference sign, 1 indicates a box or casing having a cover plate 2, which forms the base or support of all the operating parts.

80 3 denotes a rigid frame or casting inset in the cover 2, and having a bearing 4, in which is journaled a vertical spindle 5.

85 6 indicates the record disk which is removably secured to the spindle 5 by any suitable clamping device 7. The spindle 5 is driven and controlled in its movement by any suitable means, such, for example, as a spring motor 9, and governor B.

90 A practical construction of the means for driving and controlling the recording medium forms the subject of a companion application, Serial No. 396,845 filed herewith, and these features need not therefore be further considered in this case.

95 Upon the rigid frame or casting 3 I provide a round rigid rod 10, which constitutes the main guiding means for the carriage mechanism. This rod 10 is supported in a direction parallel to the face of the recording medium 6, by suitable journal bearings 11, which permit both a longitudinal movement of said rod and an angular movement on its axis. At a suitable point along the length of this rod there is fixed a frame 12 (see Fig. 6), 100 which constitutes the main frame of the carriage. This frame being fixed to the rod 10, it is clear that it partakes of any longitudinal or angular movement thereof.

105 13 denotes a counterweight forming part of the carriage frame 12, so as to produce a force tending to tilt the carriage, together

with its rod 10, into a position with its left-hand portion upward in Fig. 6.

14 indicates a lead screw journaled in the rigid frame or casting 3 and rotated commensurately with the recording medium 6, by the intermeshing worm gears 8 and 16 on the spindle 5 and the said lead screw respectively. The carriage 12 has a portion 17 which is adapted to engage the lead screw 16 when tilted upward thereagainst by the counterweight 13. This portion 17 is threaded to correspond to the lead screw and constitutes a nut to feed the carriage in connection therewith. It will be evident that when the carriage 12 is in this relation that it will be fed longitudinally by the rotation of the lead screw, the motion being permitted by the longitudinal sliding movement of the rod 10 in its journal bearings. The upwardly tilting movement under the influence of the counterweight 13 by which the threaded part 17 is engaged against the lead screw, is permitted by the angular movement of the rod 10 in its journal bearings.

25 The carriage 12 has a central hollow portion 18, the material being entirely cut away so as to expose the rod 10 therein. In this cut-away portion or cavity there is journaled loosely on the rod 10, a sleeve 19, having a 30 pair of laterally projecting arms 20. 21 indicates a spring surrounding the sleeve 19 and engaging a lug 22 thereon, and also the frame 12 so as to impart an angular movement to said sleeve 19 with relation to the frame 12. The sleeve 19 has a free angular movement on the rod 10 under the influence of its spring 21, but is constrained against any independent longitudinal movement by the side members 12' of the frame 12, which 35 engage the ends of the sleeve, and act as collars therefor. The form and tension of the spring 21 is such as to impel the arms 20 of the sleeve 19 upwardly with respect to the frame 12. The lug 22 in addition to the 40 function above noted, has an additional function in limiting the upward movement of the arms 20 under the tension of the spring 21. For this purpose the lug 22 engages a protuberance 12" on the inside of the 45 counterweight 13, or other convenient point of the carriage frame.

50 At the upper ends of the arms 20 there are cone or pivot bearings 23, between which is journaled a small block 24, preferably of insulating material. 25 and 26 are magnets inset in this block, and preferably at equal distances to each side of the pivotal axis of support thereof. The magnets 25 and 26 are the recording and reproducing and the 55 erasing magnets of the telephone.

60 It is obvious that any equivalent supporting holding frame, lever, or other means may be employed for supporting the telephone magnets in place of the construction of block 65 24, as shown.

In addition to the above features of construction, there is provided a depending bail 27, which depends downwardly from the rod 10 in loosely swinging relation therefrom, but constrained against independent longitudinal movement by the parts 12' of the frame 12, which act as collars for this bail, in addition to their other functions. At the bottom of the bail there is a projecting stud or studs 28, which are guided in a slot 29, in the casting 3, parallel to the direction of movement of the carriage. One of these studs has certain functions in controlling the speed of the recording medium, as fully set forth in my companion application above referred to. 75 There is also provided a handle or similar device 30, at the end of the rod 10, by which it may be manually moved either longitudinally or angularly in its supporting frame 1.

The operation is as follows: Assuming the 85 parts are in the relation shown, with no record disk in the machine, it is evident that the carriage frame 12 is tilted by its counterweight 13, which causes the threaded part or nut 17, to engage the lead screw. Entirely 90 independently of this, the block 24, carrying the telephone magnets, is impelled upward by the spring 21 acting on the sleeve 19. The upward movement under this spring tension is, however, limited by the lug 95 22 engaging the stop 12". If now a record disk be clamped upon the spindle in the relation shown in Fig. 2, the magnets 25 and 26 will be engaged thereby and depressed against the tension of spring 21. The tension of this spring is, however, much lighter than the force of the counterweight 13, so that the engagement of the nut 17 with the lead screw is not disturbed. If the machine is now started, the carriage, together with 105 the rod 10, will be fed longitudinally by the lead screw and the magnets will trace a continuous spiral path on the lower surface of the disk. Both magnets are borne against the disk with a certain degree of spring tension 110 obtained from the spring 21, and this tension is divided between the two magnets in exact equality by reason of the equalizing lever construction by which they are mounted on the supporting arms 20. This construction not only keeps the magnets maintained against the disk with an exactly equal and predetermined pressure, but exactly 115 compensates for any unequal or wobbling movement of the disk in its rotation. It will be evident that the range of up and down movement of the arms 20 is sufficient to accommodate the largest lateral or wobbling movement of the disk which ordinarily occurs, so that the spring 21 is always effective 120 to perform its function in keeping the magnets against the disk with unvarying efficiency. As the disk almost always wobbles more or less, and sometimes, when carelessly inserted, to a very considerable extent, this 125 130

feature of the construction is an exceedingly important one. When the carriage has been fed to the limit of its movement in either direction, it is quickly and conveniently returned by means of the handle 30 which is tilted slightly and then pushed inward or outward. This first causes the disengagement between the nut 17 and the lead screw and thereafter the carriage can be freely moved to any position desired where it is automatically reengaged upon the lead screw by the weight 15. It is evident that this repositioning of the carriage can be done at any time in its movement whether or not it has arrived at the limit of its normal feed. Should the apparatus be allowed to run after the carriage has arrived at the normal limit of its feeding movement, no harm is done, because the nut 17 merely passes on to an unthreaded portion of the lead screw where it will not be further impelled longitudinally.

While I have shown a counterweight 13 and a spring 21 in the above construction, it is evident that any desired tensioning means may be employed. The means for tensioning the nut 17 against the lead screw may be as strong as required, while the tensioning means for the block 24 should be comparatively light. By reason of the construction shown, it is evident that the tensioning means of the nut 17 against the lead screw is wholly independent of and has no effect on the tensioning engagement between the telephone magnets and the recording medium, notwithstanding that these parts are made a part of the same carriage frame and mounted on the same guiding and tilting rod 24.

What I claim, is:—

- 40 1. In a telephone, a carriage longitudinally and angularly movable on a fixed axis, feeding means for said carriage, means for tilting said carriage on said axis whereby it is disengaged from its feeding means, and a telephone magnet yieldingly supported by said carriage.
2. In a telephone, a carriage longitudinally and angularly movable on a fixed axis, feeding means for said carriage, means for tilting said carriage on said axis whereby it is disengaged from its feeding means, and a telephone magnet also angularly movable on said axis and yieldingly supported from said carriage.
- 55 3. In a telephone, a carriage longitudinally and angularly movable on a fixed axis, feeding means for said carriage, means for tilting said carriage on said axis whereby it is disengaged from its feeding means, a device pivoted on said axis and longitudinally movable with the carriage, and a part having a telephone magnet and an erasing magnet, and pivoted on said device.
- 60 4. In a device of the class described, a continuously rotating record medium, a lead

screw rotating commensurately therewith, a carriage having a yielding engagement with said screw, yielding supporting means on said carriage, and a telephone magnet yieldingly carried by said means.

5. In a telephone, a continuously movable medium, a carriage movable parallel thereto and tilttable on its axis of longitudinal movement, yielding means on said carriage, and a block or frame having a plurality of devices coöperating with said medium, and yieldingly supported on said means.

6. In a telephone, a continuously movable medium, a lead screw, a carriage in yielding engagement with said lead screw, yielding means on said carriage, a block or frame pivoted on said means, and telephone magnets supported by said block.

7. In a telephone, a continuously rotating disk having a smooth face, a carriage movable over said face, a block or frame yieldingly and tiltably supported on said carriage, and a pair of telephone magnets supported by said block and moving on said disk symmetrically with respect to a single radial line of direction, whereby they trace or track a single path on said disk.

8. In a telephone, a continuously movable medium, a lead screw connected to be rotated therewith, a carriage movable parallel to said medium and screw and having tilting means yieldingly pressed into engagement with said screw to feed the carriage, a telephone magnet, and independent spring pressed means pivoted on said carriage for supporting said magnet.

9. In a telephone, a continuously moving medium, devices engaging said medium, means for yieldingly supporting said devices, and a carriage movable and tilttable on a fixed axis for yieldingly supporting said means.

10. In a telephone, a continuously rotating disk, a pair of telephone magnets rigidly connected together and movable over the face thereof, means for supporting said magnets, a lead screw, and a carriage yieldingly engaging said lead screw and yieldingly supporting said means.

11. In a telephone, a continuously movable medium, a carriage guided parallel thereto, an arm pivoted to said carriage, a telephone magnet on said arm, and a spring for impelling said arm away from said carriage.

12. In a telephone, a continuously movable medium, a carriage movable parallel thereto, feeding means for said carriage, means for tilting the carriage to disengage it from its feeding means, and a telephone magnet supported by said carriage.

13. In a telephone, a continuously movable medium, a carriage movable parallel thereto, feeding means for said carriage, means for tilting the carriage to disengage it from its feeding means, and a telephone magnet supported by said carriage.

magnet yieldingly supported by said carriage and yieldingly pressed therefrom toward said medium.

14. In a telephone, an angularly and longitudinally movable rod, a carriage fixed thereto and having a threaded portion, a lead screw in the path of said threaded portion, means for tilting said rod to disengage the carriage from the lead screw, and a telephone magnet yieldingly supported from said carriage.

15. In a telephone, a longitudinally and angularly movable rod, a carriage fixed thereto and having a threaded portion, a lead screw, means for yieldingly pressing said threaded portion against said lead screw, means for tilting said rod whereby the carriage is disengaged from the lead screw, a telephone magnet pivotally supported on said carriage, and a spring for impelling said magnet with respect to said carriage.

16. In a telephone, an angularly and longitudinally movable rod, a carriage fixed thereto and having a central cut-away portion or cavity, a sleeve loosely journaled on said rod within said cavity, means for yieldingly impelling said sleeve with respect to said carriage, and a telephone magnet supported by said sleeve.

17. In a telephone, an angularly and longitudinally movable rod, a carriage fixed thereto, a sleeve loose on said rod and fixed against longitudinal movement thereon by said carriage, arms projecting from said sleeve, and a telephone magnet carried by said arms.

18. In a telephone, a carriage, a sleeve pivoted with respect thereto and yieldingly impelled therefrom, arms projecting from said sleeve, a block pivoted to said arms, and telephone magnets carried by said block on either side of said pivotal axis.

19. In a telephone, a lead screw, a carriage having a threaded portion engaging the same, means for yieldingly pressing said threaded portion against the screw, a telephone magnet movably supported with respect to said carriage, and resilient means for impelling said magnet with respect to said carriage, the tension of said resilient means being independent of the force of said yielding means.

20. In a telephone, a rod angularly and longitudinally movable, a carriage wholly supported thereby, means for tilting said carriage and rod, a lead screw engaged by said carriage in its tilting movement, a telephone magnet movably supported with respect to said carriage, and resilient means for impelling said magnet with respect to said carriage and acting wholly independently of the tilting movement of the carriage against said lead screw.

21. In a telephone, a carriage, a lead screw, and a telephone magnet, and two

separate yielding means entirely independent of one another and acting respectively to impel the carriage into engagement with said screw and said magnet with respect to the carriage.

22. In a telephone, a longitudinally and angularly movable rod, a carriage wholly supported thereby and having a threaded portion, a lead screw, means for impelling the carriage to engage said lead screw with its threaded portion, a telephone magnet, and yielding means having its tension entirely independent of the force of said first named yielding means and impelling said magnet with respect to the carriage.

23. In a telephone, a continuously rotating steel disk, a pair of telephone magnets, a pivoted block or frame supporting said magnets in equal-bearing engagement against said disk, yielding means for supporting said pivoted block or frame, and a carriage supporting said yielding means and movable across the face of said disk.

24. In a telephone, a carriage longitudinally movable and tilttable on a fixed axis, feeding means therefor, means for tilting said carriage on its axis to disengage it from its feeding means, a telephone magnet, and means pivoted in the carriage and yieldingly impelled with respect thereto for supporting said recording and reproducing magnet.

25. In a telephone, a continuously rotating steel disk, a carriage movable over the face thereof, and a pair of magnets, one of which is for erasing a record, both carried by said carriage.

26. In a telephone, a continuously rotating steel disk, a carriage movable with respect to the face thereof, a pair of magnets supported by said carriage to press yieldingly and independently against said disk, one of said magnets constituting an erasing means.

27. In a telephone, a continuously rotating steel disk, a carriage movable with respect to the face thereof, and a pair of magnets supported by said carriage to bear equally and yieldingly against said disk, one of said magnets constituting an erasing means.

28. In a device of the class described, a continuously rotating record medium, a carriage movable over the face thereof, and a pair of devices rigidly connected together and both supported by said carriage to bear equally and yieldingly against said medium during the rotation thereof.

29. In a device of the class described, a continuously rotating record medium, a carriage movable over the face thereof, a block or frame fulcrumed on said carriage, and a pair of devices carried by said block or frame on the opposite sides of said fulcrum and yieldingly borne against the medium thereby.

30. In a device of the class described, a

70

continuously rotating record medium, a carriage movable over the face thereof, a block or frame fulcrumed on said carriage, devices carried by said block or frame at equal distances on either side of said fulcrum and borne equally and yieldingly into engagement with said medium thereby.

31. In a device of the class described, a continuously rotating disk, a carriage movable over the face thereof, a pair of devices rigidly connected together and supported by said carriage to bear against said disk, said carriage being guided to position said devices to always track or trace a single path on the disk.

32. In a device of the class described, a continuously rotating record medium having a perfectly smooth face, a carriage movable over said face thereof, and a pair of devices supported by said carriage to bear equally and yieldingly against said medium, one of said magnets being positioned to exactly trace or track the path of the other.

33. In a device of the class described, a continuously rotating steel disk having a smooth face, a carriage movable over said face, and telegraphone magnets supported by said carriage to bear against said medium during the rotation thereof, each of said magnets being positioned to trace or track the path of another.

34. In a device of the class described, a

continuously rotating record medium, a carriage movable over the face thereof in a radial line of direction, and a pair of devices supported by said carriage to bear against said medium symmetrically on either side of said radial direction line, whereby one of said devices exactly traces or tracks the path of the other at all times.

35. In a device of the class described, a continuously rotating record medium, a carriage movable over the face thereof in a radial line of direction, and devices symmetrically arranged with respect to said radial direction line, whereby one exactly traces or tracks the path of another.

36. In a device of the class described, a continuously rotating record medium, a carriage movable over the face thereof on a radial line of direction, and a pair of devices supported by said carriage to bear equally and yieldingly against said medium during the rotation thereof, said devices being symmetrically disposed with respect to said direction line, whereby one exactly tracks or traces the path of the other.

In witness whereof, I subscribe my signature, in the presence of two witnesses.

HARVE R. STUART.
